(57) **CLAIM**

The ornamental design for an accumulator, as shown and described.

DESCRIPTION

FIG. 1 is a perspective view of an accumulator showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and

FIG. 7 is a bottom plan view thereof; and,

FIG. 8 is a top plan view of an alternative embodiment of an accumulator showing my new design, with the view of the accumulator of FIG. 8 being similar to the view of the accumulator of FIG. 6, and further with the accumulator of FIG. 8 being configured similarly to the accumulator of FIG. 6.

The broken lines shown represent unclaimed subject matter and form no part of the claimed design.
